UNITED STATES PATENT OFFICE.

JOHN W. ALTMYER, OF CEDAR RAPIDS, IOWA.

HAT HANGER.

Application filed November 18, 1922. Serial No. 601,840.

To all whom it may concern:

Be it known that I, JOHN W. ALTMYER, a citizen of the United States, residing at Cedar Rapids, in the county of Linn and State of Iowa, have invented a new and useful Improvement in Hat Hangers, of which the following is a specification.

This invention relates to hat hangers, and has for its object the provision of an improved device which is capable of supporting a hat against the under side of an automobile top in a manner to prevent injury to the hat and at the same time effectively maintain the hat in position.

The present invention is a continuation of my former application, Serial No. 528,238, filed January 10, 1922.

The invention will be best understood from a consideration of the following detailed description taken in connection with the accompanying drawing forming part of this specification, with the understanding, however, that the invention is not confined to any strict conformity with the showing in the drawing, but may be changed and modified so long as such changes and modifications mark no material departure from the salient features of the invention as expressed in the appended claims.

In the drawing:—

Fig. 1 is a perspective view of a part of an automobile showing the hanger mounted upon the under side of the automobile top.

Fig. 2 is a bottom plan view of the hanger detached.

Fig. 3 is a perspective view on an enlarged scale showing the tab and hook.

Fig. 4 is a plan view of the hanger having stretching means connected therewith.

Fig. 5 is a detail view of a part of the stretching means.

Fig. 6 is a plan view of a slightly modified form of the invention.

Referring more particularly to the drawing, 1 designates an automobile, upon which is mounted a top 2, having cross bows 3 to which my invention is particularly to be attached. The invention includes a block 4 having an interior cavity 5, which is concealed when the block is attached to the cross bow 3 by means of a screw or the like, in the manner shown. An elastic member 6 has its ends inserted through an opening in the block 4 and securely fas-

tened in a clip 7 within the block. The intermediate portion of the member 6, therefore, forms a loop 8 to which a tab 9 is slidably secured by means of an eyelet 19, or the like. The tab may be provided with one or more holes, as indicated at 10 and 11, either one of which, when the device is stretched, may be received by a hook 12 secured to one of the cross bows at a suitable distance from the block 4. The elastic member 6 is of suitable length to receive the crown of a hat, and the block 4 and hook 12 are spaced a suitable distance apart so that the hat will be securely held to the top of the automobile, as indicated in Fig. 1.

For the purpose of holding a soft hat, which is liable to be damaged by too great a pressure, it may, in some instances, be desirable to use a stretcher in connection with the hanger, for the purpose of spacing the sides of the loop a suitable distance from each other. Such a device is shown in Figs. 4 and 5, and comprises a pair of channel rods 13, each of which is pivotally mounted at one end on a pin 14 between a pair of ears 15 formed integrally with a collar 16, the outer ends of the collar being inturned and clamped upon the flexible element to prevent movement of the collar relative thereto. Preferably, the collars 16 are offset with respect to each other, as shown in Fig. 4, and the opposite ends of the rods 13 are pivotally secured to the collars 17, which are freely slidable upon the opposite strand. A spring 18 is coiled about the pivot pin 14 to normally urge the rods into a position transverse to the strands of the loop.

In using my hanger, after the hat has been inserted, the user may, by grasping the tab 9, stretch the same sufficiently to firmly hold the hat and insert the hook 12 through either of the holes 10 or 11. It is obvious, also, that the device may be stretched further, if desired, and the hook inserted through the loop 8. In Fig. 6, I have shown a slight modification, in which the tab 9^a is used merely for the purpose of providing a convenient finger hold, and the loop is placed over the hook 12^a, which, in this form, is made somewhat wider than the hook 12.

From the foregoing description, it will be seen that I have invented a very con-

venient and useful device for holding the hats of automobilists, which will prevent the same from being crushed or blown away, and one which may be manufactured at a 5 comparatively small cost.

It is obvious that the invention is not limited for use in connection with automobiles but may be employed for other purposes.

10 What is claimed is:—

1. A hat holder comprising a block, an elastic member having its ends secured to said block in spaced relation said block having means for securing it to a fixed part, the intermediate portion of the elastic member forming a loop, a hook also secured to the fixed part and spaced from the block a greater distance than the normal length of said elastic member, and a tab connected to 15 the looped portion of the elastic member providing means for stretching said member and connecting it with the hook to hold it in stretched position.

2. A hat holder comprising a block, 25 adapted to be secured to a fixed part, an elastic member having its ends secured to said block in spaced-apart relation, the intermediate portion of the elastic member forming a loop, a hook also secured to the fixed part and spaced from the block a greater 30 distance than the normal length of said member, said hook being connected to the looped portion of the elastic member when the latter is stretched for holding said member in stretched position, the sides of said member maintaining their spaced relation at all times.

3. A hat holder comprising a block, an elastic member having its ends secured to 40 said block, the latter having means for securing it to a fixed part, the intermediate portion of the elastic member forming a loop, a hook secured to the fixed part, and a tab mounted on the looped portion and 45 having a hole adapted to receive the hook when the elastic member is stretched.

4. A hat holder comprising an elastic member having two strands, means for rigidly connecting one end of said member 50 to a fixed part and holding the strands in spaced-apart relation, a hook also secured to a fixed part, and a tab mounted on the other end of said member and having a hole adapted to receive the hook when the elastic 55 member is stretched.

5. A hat holder comprising an elastic member having its ends secured to a fixed part, the intermediate portion of the elastic member forming a loop, a hook also secured 60 to the fixed part and adapted to be connected to the looped end of the elastic member, and means for stretching the portions of the elastic member between the looped

portion and the ends of said member into spaced relation with each other.

65

6. A hat holder comprising an elastic member doubled upon itself to form two parallel strands, the ends of the elastic member being secured to a fixed part, the intermediate portion of the elastic member forming a loop, a hook also secured to a fixed part and adapted to receive the looped end of the elastic member, and means for stretching the strands of the elastic member into spaced relation to each other, said means being slidably mounted at one end on one of the strands and secured at its other end to the other strand.

75

7. A hat holder comprising a hollow block adapted to be secured to a fixed part, an elastic member having its ends passed through the side of the block and secured therein, the intermediate portion of the elastic member forming a loop, a hook also secured to the fixed part and adapted to receive the looped end of the elastic member, and means for stretching the portions of the elastic member between the looped portion and the ends held by the block, said means including a pair of rods each pivotally mounted upon an opposite strand of the elastic member and having sliding engagement with the other strand.

80

8. A hat holder comprising an elastic member doubled upon itself to form two parallel strands, the ends of the elastic member being secured to a fixed part, the intermediate portion of the elastic member forming a loop, a hook secured to the fixed part and adapted to receive the looped end of the elastic member, a pair of rods each pivotally mounted upon an opposite strand and having a sliding engagement with the other strand for extending the strands in spaced relation to each other, and means for urging the rods to a position at right angles to the strands.

85

9. A hat holder comprising an elastic member doubled upon itself to form two parallel strands, the ends of the elastic member being secured to a fixed part, the intermediate portion of the elastic member forming a loop, a hook also secured to the fixed part and adapted to receive the looped end of the elastic member, sleeves diagonally disposed relative to each other and slidably upon adjacent strands, a collar spaced from each sleeve and secured on the adjacent strands, and rods pivotally connecting an adjacent sleeve and collar transversely of the strands.

100

In testimony that I claim the foregoing as my own I have hereto affixed my signature.

105
